TIMING CONTROL CIRCUIT

Ben Eisenberg, Brooklyn, N. Y., assignor to Lektra Laboratories, Inc., New York, N. Y., a corporation of New York

Application September 27, 1941, Serial No. 412,644

7 Claims. (Cl. 175—320)

This invention relates to the art including electronic circuits useful for the precisely timed control of the action of controlled devices, and more particularly to such circuits for energizing or de-energizing a controlled device for predetermined precise intervals of time.

A typical application of the present invention is in the field of electric shock therapy, and it will be described with respect to such an application, although in no way restricted thereto.

The administration of an electric shock of suitable voltage and current for a definite length of time has been found to be very beneficial in the treatment of many kinds of paranoia, especially in the treatment of manic depression and schizophrenia. However, in order to obtain beneficial results in the treatment of these mental ailments without physical injury to the patient, it is important that the proper magnitude of voltage and current be used, and for the proper time interval.

It is an object of the present invention to provide improved timing circuits, especially adapted for, but not restricted to, electric shock therapy, which will effect a predetermined operation for an accurately defined and easily controllable time interval.

It is a further object of the present invention to provide such improved timing circuits in which sharp and positive energization and de-energization of a relay is effected by a simple circuit by which the commencement of energization (or de-energization, as the case may be) acts to increase the energization (or de-energization) so that the only stable condition thereafter is that of complete energization (or de-energization), which is attained in a very short time.

Further objects and advantages of the present invention will be apparent from the following detailed description, in which the invention is embodied in concrete form.

In the drawing,

Figure 1 shows a schematic wiring diagram of an electric shock therapy device in which the present invention may be used.

Figure 2 shows a schematic wiring diagram 45 of the current-pulse meter of the device of FIG. 1.

Figure 3 shows a schematic wiring diagram of one form of timing circuit according to the present invention, suitable for use with the circuit of Figure 1;

Figure 4 shows a schematic wiring diagram of a modification of the circuit of Figure 3.

Referring to the drawing, in Figure 1, reference numeral 1 represents the input terminals 50

of my electric shock therapy device, which are adapted to be connected to any suitable source of alternating current, such as the conventional alternating power supply. Connected to terminals 1, through a power switch 2, is a voltage adjusting device illustrated as being a variable auto-transformer 3, by means of which the voltage to be applied to the patient may be adjusted to the proper value as determined by diagnosis and measurement. Any suitable voltage adjusting means may be used here. This voltage may be measured by voltmeter 4.

Connected across the adjusted voltage output of the voltage regulator 3 is a series circuit comprising a current limiter 6, a current meter 7, a timer 8 and the applying electrodes 13, connected in this circuit by the throw-over switch 9, when in the right-hand position.

When switch 9 is thrown to the left, or "test" 20 position, the electrodes 13 are connected through a resistance meter 11, which may be of any conventional type, to a suitable source of direct voltage, indicated by terminals 12. Switch 9 also has an open position, in which electrodes 13 are 25 completely disconnected from the rest of the apparatus.

Current limiter 6 may be any suitable device 30 which will insure that the maximum current delivered to the patient through the applying electrodes 13 does not exceed a safe value. In a preferred embodiment, this current limiter 6 may take the form of an adjustable current-operated circuit breaker which may be set to a value just exceeding the described current dose.

Current meter 7 is used to give the operator 35 a direct and instantaneous indication of the amount of current administered to the patient. For this purpose a special circuit is necessary, because of the relatively short duration of applied current, which lasts only for a time interval of the order of one-tenth of one second. Fig. 2 shows a suitable circuit for such a current meter.

Input terminals a—b of meter 7 are connected to the primary winding 17 of a current transformer 18 whose secondary winding 19 is connected through condensers 24, 26 across double diode 23, whose two diode sections are connected in parallel to provide a low impedance load for transformer 18. Any diode of sufficiently low impedance may be used in place of double diode 23. In order that the meter as a whole shall offer as low an impedance as possible to the applied current, the primary winding 17 of transformer 50 18 is shunted by a resistor 16 having a very low

resistance value which may be of the order of 5 ohms.

In order that transient pulses caused by opening or closing of line switch 2 or by conditions on the line shall not adversely affect the indication of meter 7, the secondary winding 19 of transformer 18 is shunted by a condenser 21 which provides a low impedance path for the transient impulses, which are being almost entirely of relatively high frequencies.

Since the current pulses to be measured are of quite small duration, it is essential that the indication of meter 7 be given without appreciable lag. Also, the indication must be maintained for a reasonable length of time after the initiation of the current in order that the reading may be conveniently made. These two requirements are in a sense contradictory, since, in general, a circuit which responds quickly cannot maintain its condition for any length of time. For a quick response, it is necessary that the load circuit of the transformer 18 be of low time constant. On the other hand, the requirement that the circuit condition be maintained until a good reading can be obtained requires a rather high time constant. The circuit of Fig. 2 is especially designed to overcome this apparent contradiction.

In order that the circuit shall respond quickly, the time constant of the load circuit of diode 23 is made small by using no load resistor and a small capacitance, derived from the series connection of condensers 24 and 26. Of these condensers, condenser 24 is chosen with fairly small capacitance, and condenser 26 with rather high capacitance. Hence, their series connection will have small capacitance, permitting a low time constant as is desired.

To obtain a maintained meter reading, the voltage across the condenser 26 is used. Because of the high capacitance of condenser 26, its voltage will be held practically constant substantially without decaying for an appreciable time, sufficient to obtain the desired reading, if connected to a high resistance circuit. Accordingly, one terminal of condenser 26 is grounded as at 27, and the other is connected to the control grid 33 of one section of a double triode tube 32, through a resistor 31. The time constant of the output circuit of the diode 23 is determined by condenser 26 (already of high capacitance) together with resistance 31 and the grid resistance of tube 32. Switches 28 and 29 are provided to discharge condensers 24 and 26 after the reading has been obtained. These switches are necessitated by the high time constant of the circuit of condenser 26, which maintains the voltage on condenser 26 for a substantial time. Switches 28 and 29 may be ganged, as shown.

Double triode 32, which may be replaced by any pair of similar amplifying tubes, and its associated circuit elements act as a bridge type electronic voltmeter to measure the voltage across condenser 26. The four arms of this bridge circuit are formed respectively by the two sections of tube 32 and two resistors 43 and 44, which are the load resistors for the two tube sections, meter 47 being connected directly from plate to plate of the two tube sections. Resistor 44 is made adjustable.

The two cathodes 38, 39 are connected directly together, and to ground through their common biasing resistor 41. The control grid 34 of the second triode section is also connected to ground, through the grid leak resistor 42. The common terminal of resistors 43, 44 is connected

to the positive terminal of a suitable source of direct voltage, whose negative terminal is grounded.

In operation, switches 28 and 29 are momentarily closed and then reopened. Then, with zero input to transformer 18, the bridge is balanced by adjusting variable resistor 44, until the meter reading is zero, whereupon the bridge is in balanced condition. Then any current passing through the primary winding of transformer 18 will produce a corresponding and proportional direct voltage across condenser 26, which voltage will persist for a substantial period because of the high time constant of the output circuit of diode 23. This voltage will produce an unbalance in the meter bridge arrangement, by causing the current in arm 44 to change, so that a definite indication is produced on meter 47, which will persist long after the initiating current pulse is over. Thus the present arrangement provides a sensitive current meter for measuring even rather short current pulses, as are met with in devices of the present type.

Figure 3 shows the schematic wiring diagram of one type of timing circuit incorporating the present invention and suitable for use as the timer 8 of Figure 1. This timing circuit comprises two electron discharge tubes, 52 and 62 shown, for illustrative purposes only, as being a pentode 52 and a beam-power tube 62. As will be more evident later, any types of known amplifier tubes may be used in place of tubes 52 and 62.

Power is supplied to the circuit by way of a voltage divider composed of resistors 82 to 86 connected in series across any suitable source of direct voltage, indicated schematically by positive terminal 78, the negative terminal being grounded as at 49. Cathode 57 of tube 52 is connected to the junction of resistors 83 and 84, while control grid 56 is connected to the junction of resistors 82 and 83, through variable resistor 79, so that the volt-drop across resistor 83 provides a fixed or normal grid bias for tube 52, subject to the changes described below. Condenser 81 has one terminal connected also to the junction of resistors 82 and 83, while the other terminal is selectively connectible to ground 49 or to grid 56, according as switch 50 is thrown to position A or to position B. Hence, in position A of switch 50, condenser 81 is charged up to the volt-drop appearing across resistor 82, while in position B it discharges through resistor 79, thereby adding a variable decaying control voltage in series with the fixed bias provided by resistor 83 for grid 56.

The anode 53 of tube 52 is energized by connection through load resistor 87 to the junction of resistors 84 and 85, while screen grid 54 is connected directly to the junction of resistors 85 and 86, and is therefore at a higher potential than that of anode 53.

Control grid 67 of tube 62 is connected directly to anode 53 and to one terminal of load resistor 87 by means of conductor 88, while the cathode 68 of tube 62 is connected to the other terminal of resistor 87 by means of conductor 89, so that the full volt-drop across resistor 87 forms the input voltage to tube 62.

Screen grid 66 and anode 63 of tube 62 are connected directly together, and both are connected to terminal 78 through relay winding 73, which forms the load impedance for tube 62. Winding 73, when energized by the flow of anode current through tube 62, draws its magnetic armature 74 against fixed contact 76, thereby completing

the control circuit $c-d$ for electrodes 13 , or for any other control circuit, represented by conductors 11 .

In operation, switch 50 is normally left in position A. Resistor 83 is so chosen that the normal plate current of tube 52 flowing in resistor 81 will produce a normal volt-drop sufficient to bias tube 62 to at least the cut-off point. Accordingly, no plate current flows to anode 63 , and relay 73 remains unenergized. Meanwhile, condenser 81 is charged to the full voltage across resistor 82 , its polarity being as indicated.

When switch 50 is thrown to position B, the full voltage of condenser 81 will appear, at the first instant, across resistor 79 , and will be in series with the voltage across resistor 83 . The negative bias of control grid 56 is thereby increased, reducing the plate current flowing through resistor 81 . Therefore the volt-drop across resistor 81 is reduced, decreasing the negative bias on grid 61 . Preferably, the increased bias on grid 56 biases tube 52 beyond cut-off, so that zero voltage remains across resistor 81 , and tube 62 begins to conduct at once, energizing relay 73 . However, cut-off bias is not necessary.

As soon as plate current begins to flow in tube 62 , the volt-drops across resistors 82 , 83 and 84 increase, due to the added current flowing therein because of the conductive state of tube 62 . The increased voltage across resistor 83 (which is common to the input circuit of control tube 52 and to the output circuit of power tube 62) due to this increased current drives tube 62 further towards cut-off (if not already there), thereby causing increased current flow through resistor 83 . Hence the action is cumulative, causing tube 62 to change rapidly from zero conduction to full conduction and energizing relay 73 almost instantaneously.

Relay 73 is maintained energized so long as the sum of the volt-drops across resistors 79 and 83 exceeds the cut-off voltage of tube 52 . However, condenser 81 gradually becomes discharged through resistor 79 , whose volt-drop therefore decreases with time. At the instant that the volt-drop sum becomes less than the cut-off voltage, the reverse sequence of operations is effected, whereby relay 73 becomes instantly de-energized.

Hence, the time interval during which relay 73 remains energized depends directly upon the discharge rate of condenser 81 . This may be adjusted by adjusting the resistance of variable resistor 79 , thus affording a sensitive and accurate control of the time interval of energization.

It will be clear that the present timing circuit is not restricted in its use to the particular one shown, but may be used wherever it is desirable to close a circuit for an accurately adjustable time interval. Also, by slight changes in the disposition of armature 74 or by the addition of other contacts and contact 76 , many other uses may be found for this circuit. Typical other uses may be for such applications as timing exposures in photographic printing, or in timing X-ray treatments.

Switch 50 may be made as a momentary contact switch, normally in position A, but which may be held in position B. Then, in operation, the operator holds the switch in position B until treatment is completed and then releases the switch, thereby automatically recharging condenser 81 , in preparation for the next treatment. Thus, full control of treatment is in the operator's hands, and may be terminated at any time. This provides an additional safety feature, by releasing

switch 50 to position A, so that tube 62 is blocked and the relay 73 is released at once to terminate the treatment.

Figure 4 shows a modification of the circuit of Figure 3. This circuit is generally the same as that of Figure 3, except that screen grid 54 of tube 52 is here connected to cathode 57 , load resistor 87 is removed, and beam-power tube 62 has been replaced by an ordinary tetrode 84 , whose screen grid 92 is connected to its cathode 91 . The remainder of the elements and connections are the same as in Figure 3.

The operation of this circuit is believed to be as follows: With switch 50 in position A, the inter-electrode capacitances of tubes 84 and 52 cause grid 89 to assume a potential intermediate to those of cathodes 57 and 91 , thereby driving tube 94 to cut-off. Throwing switch 50 to position B disturbs the equilibrium potential of grid 89 , which is connected directly to the anode of tube 52 , and causes tube 94 to start conducting. This sets into play the same cumulative action described above, and relay 73 becomes instantly energized. After condenser 81 has discharged to the proper degree, the potential of grid 89 seems to change in the negative direction, and the reverse cumulative action occurs, instantly de-energizing relay 73 . The time interval of energization is again directly responsive to the adjustment of variable resistor 79 .

Having described the various components of the system in detail, the operation of the electric shock therapy apparatus will now be described. Switches 2 and 9 are normally left in the open position, and switch 50 is left in position A. Electrodes 13 are placed in good electrical contact with chosen portions of the patient's head. Then switch 9 is thrown to the left, or "test" position, and the patient's electrical resistance is measured on resistance meter 11 . The reading thus obtained will inform the operator as to the proper adjustment of voltage adjuster 3 and the proper shock duration necessary to obtain the desired treatment. Voltage adjuster 3 and rheostat 79 of timer 8 are then set to the proper values, switch 2 is closed, and switch 9 is thrown to the right, or "treat" position. Then switch 50 is thrown to position B, whereupon treatment is at once initiated, and automatically stops after the time interval adjusted for. After treatment is completed, switch 50 must be thrown again to position A, so that condenser 81 may be recharged, before further treatment can be given.

Since many changes and modifications could be made in the devices disclosed above without departing from the spirit of my invention, the present description is to be in no way considered in a limiting sense, but merely as illustrative of the invention pointed out more particularly in the appended claims.

I claim:

1. A control circuit comprising a relay, an electron discharge tube, means connecting said relay in the output circuit of said tube, a second electron discharge tube, means directly connecting the output of said second tube to the input of said first tube, means for adjusting the normal plate current of said second tube to such a value that said first tube is blocked, whereby said relay is unenergized, means for momentarily blocking said second tube, whereby said normal plate current drops to zero and said relay becomes energized, and means responsive to flow of current thru said relay for maintaining said second tube blocked, said last two means comprising a re-

sistor connected in the output circuit of said first tube, a source of control voltage, and means connecting both said source and said resistor to said second tube input, whereby said second tube input is responsive to both said control voltage and the volt-drop across said resistor.

2. A control circuit comprising a power tube, a relay connected in the output circuit of said power tube, a control tube having an output resistor, means for connecting the volt drop across said output resistor in direct current fashion in the input circuit of said power tube, a resistor common to the input circuit of said control tube and the output circuit of said power tube, means for producing a normal volt drop across said resistor sufficient to bias said control tube to a value producing a volt-drop across said output resistor sufficient to bias said power tube beyond cut-off, and means for applying a varying control voltage to the input circuit of said control tube in series with the voltage drop across said resistor, said voltage having an initial value sufficient to overcome said normal volt-drop and block said control tube, said voltage thereafter decaying with time, whereby said control tube is initially rendered non-conductive so as to unblock said power tube and to cause current to flow through said relay and said resistor, said current thereby further blocking said control tube to maintain said relay in energized condition until decay of said voltage to a value producing less than the cut-off bias for said control tube, whereupon said control tube is then rendered conductive to block said power tube and decrease said resistor current to further unblock said control tube and immediately de-energize said relay, whereby said relay is energized only for a period determined by the decay of said voltage.

3. A control circuit comprising a power tube having a relay connected in the output circuit thereof, a control tube having an output resistor connected between the anode thereof and a source of positive voltage and a screen grid connected to a source of higher positive voltage, means connecting said resistor in the input circuit of said power tube, a resistor common to the input circuit of said control tube and the output circuit of said power tube and adapted to decrease the conductivity of said control tube in response to increased current flow through said power tube and relay, and means for applying a decaying volt-

age in series with the volt-drop across said common resistor to momentarily block said control tube, whereby said relay is energized for the time interval required for said voltage to decay to a value unblocking said control tube.

4. A control circuit as in claim 1, wherein said source comprises means for producing a decaying control voltage whereby said second tube is essentially blocked by said voltage and volt-drop and becomes unblocked after a time interval necessary for said voltage to decay to a predetermined value so that said relay current flows only for said time interval.

5. A control circuit as in claim 1, further including means for disconnecting said source from said control tube input circuit, whereby said relay current may be manually interrupted as desired.

6. A control circuit comprising a relay, an electron-discharge tube, means connecting said relay in the output circuit of said tube, a second electron-discharge tube, means directly connecting the output of said second tube to the input of said first tube, means for adjusting the normal plate current of said second tube to such a value that said first tube is blocked, whereby said relay is unenergized, means for momentarily blocking said second tube, whereby said normal plate current drops to zero and said relay becomes energized, and means responsive to flow of current through said relay for maintaining said second tube blocked, said last-named means including a resistor common to the input circuit of said second tube and to the output circuit of said first tube.

7. A control circuit comprising a relay, an electron-discharge tube, means connecting said relay in the output circuit of said tube, a second electron-discharge tube, means directly connecting the output of said second tube to the input of said first tube, means for adjusting the normal plate current of said second tube to such a value that said first tube is blocked, whereby said relay is unenergized, means for momentarily blocking said second tube, whereby said normal plate current drops to zero and said relay becomes energized, and means responsive to flow of current through said relay for maintaining said second tube blocked, and further including means for unblocking said second tube after a predetermined time interval, and means responsive to said unblocking for further unblocking said second tube.

BEN EISENBERG.
